(57) CLAIM

The ornamental design for a body mat, as shown and described.

DESCRIPTION

FIG. 1 is a front view of a body mat showing my new design;
 FIG. 2 is a rear view of the body mat;
 FIG. 3 is a right side view of the body mat;
 FIG. 4 is a left side view of the body mat;
 FIG. 5 is a top view of the body mat;
 FIG. 6 is a bottom view of the body mat; and,
 FIG. 7 is a top front side perspective view of the body mat.
 The broken lines on the article throughout the figures are illustrative of stitching forming no part of the claimed design.
